US00D607539S

(12) **United States Design Patent**
Matsumoto

(10) **Patent No.:** **US D607,539 S**
(45) **Date of Patent:** ** *Jan. 5, 2010

(54) **ELECTROMAGNETIC VALVE**

(75) Inventor: **Takumi Matsumoto**, Tsukubamirai (JP)

(73) Assignee: **SMC Corporation**, Chiyoda-ku, Tokyo (JP)

(**) Term: **14 Years**

(21) Appl. No.: **29/312,306**

(22) Filed: **Oct. 14, 2008**

(30) **Foreign Application Priority Data**

Apr. 18, 2008 (JP) 2008-010118

(51) **LOC (9) Cl.** **23-01**

(52) **U.S. Cl.** **D23/233**

(58) **Field of Classification Search** D23/233-237, D23/244-249; D15/5, 7, 199; 137/554, 137/557, 560, 882, 884, 343, 625.64, 269, 137/271; 251/12, 130, 129.04, 219, 331; 4/305
